UNITED STATES PATENT OFFICE.

ELI C. HORNE, OF JASPER, FLORIDA.

COTTON-GIN.

SPECIFICATION forming part of Letters Patent No. 236,591, dated January 11, 1881.

Application filed June 17, 1880. (Model.)

To all whom it may concern:

Be it known that I, ELI C. HORNE, of Jasper, in the county of Hamilton and State of Florida, have invented a new and useful Improvement 5 in Cotton-Gins, of which the following is a specification.

My invention consists in a novel construction, arrangement, and combination of devices for ginning cotton by the action of a roller, 10 blades, and fingers, as hereinafter described.

In the accompanying drawings, Figure 1 is an elevation of a machine embodying my improvements. Fig. 2 is a vertical section taken in the line *x x* of Fig. 1.

15 Similar letters of reference indicate corresponding parts.

The working parts of the apparatus are supported by a wrought-iron frame, A, of triangular form in its cross-section, the base resting 20 on the ground.

In the upper part of the frame A is journaled a roller, B, and immediately over this roller is a blade, C. This blade is arranged so as to lie against the side of the roller B, and 25 is provided with springs D, through which pass the bolts *e*, by which the blade is fastened to the frame. These springs allow the blade to yield to any obstructions which may find their way between it and the roller.

30 In the lower part of the frame A is journaled a crank-shaft, F, on one end of which is a pulley, *f*, through which it may be driven by a belt from a wheel, *e*, on the shaft of the roller B. The shaft F is provided with two cranks, to 35 which are attached the lower ends of two rods, G G, provided with gibbs and keys for tightening them when necessary. The upper ends of

the rods G carry a blade, H, which works immediately under the blade C, and the upper edge of which is slightly oblique with relation 40 to the lower edge of the said blade C. The rear side of the blade H is connected by rods *i* with a rock-shaft, J, the ends of which are journaled in two arms, K K, extending rearward from the upper part of the frame A. 45

On the upper sides of the arms K rests the feed-board L, which is inclined downward toward the roller B, and has its lower edge provided with fingers *l*.

The cotton to be ginned is placed on the 50 feed-board L, and fed by its own weight to the ends of the fingers *l*, where it is engaged by the edge of the reciprocating blade H, which presses it upward between the surface of the roller B and the edge of the blade C; after 55 which it is carried around by the roller B, and deposited on an inclined plane, M, formed on the front side of the frame A.

I am aware that two reciprocating blades, one above and the other below the roll, have 60 been heretofore employed in cotton-gins; but

What I claim is—

The combination, with the roller B, of a stationary superposed blade, C, yieldingly held to the face of roll, and a subjacent reciprocating blade, H, having its upper edge arranged obliquely to the lower edge of the blade C, whereby the cotton is pressed by the blade H between the blade C and the roll, as and for the purpose specified. 65

ELI CROOM HORNE.
